Fig. 10

Fig. 11

Fig. 13

FIG. 1 is a perspective view of a house showing my new design;

FIG. 2 is a top plan view thereof;

FIG. 3 is a side elevational view thereof;

FIG. 4 is a top plan view of one modified form thereof;

FIG. 5 is a side elevational view of the first modified form thereof.

This is a continuation-in-part of my pending design application Ser. No. 19,606, filed Oct. 17, 1969 and now abandoned.

I claim:

The ornamental design for a house or similar article, as shown and described.
